BENDING MACHINE ROLL

Arthur T. Yates, West Seneca, N. Y., assignor to
Buffalo Forge Company, Buffalo, N. Y.

Application March 25, 1932. Serial No. 601,200

12 Claims. (Cl. 153—57)

This invention relates to machines for bending metal bars and the like, and particularly to improvements in the construction of bending rolls used on machines of this kind.

5 The objects of this invention are to provide a bending machine in which means are provided for adjusting the grooves in the bending rolls so that the groove on the inside roll will be of greater width than the grooves on the outside rolls; 10 also to provide bending machine rolls with adjusting means, whereby both side walls of the groove in a roll may be adjusted toward and from the center of the groove; also to provide a bending roll having means adjacent to the outer end 15 thereof for conveniently adjusting both side walls of the groove in the roll; also to improve the construction of bending rolls of this kind in other respects hereinafter specified.

In the accompanying drawing:

20 Fig. 1 is a plan view of a set of bending rolls;
Fig. 2 is a sectional view thereof, on line 2—2,
Fig. 1.

My improvement may be applied to a bending machine of any suitable or desired construction, 25 and is particularly desirable for use in connection with rolls used for bending flat bars on edge. When this is done the cross section of the bar becomes changed by the bending operation, the inner portion or edge of the bar, i. e., the portion 30 nearest to the radius of curvature, becoming enlarged or upset as indicated by the cross section of the bar X shown in Fig. 2. In order to accommodate the grooves in the bending rolls to receive such enlarged edge of the bar, I provide 35 narrower grooves on the outer bending rolls than on the inner roll, and I also provide means for spacing the side walls of each of these grooves at equal distances from the central plane of the bar.

In bending rolls heretofore made, each roll 40 consisted of two parts, one of which was fixed to its roll shaft and the other of which was adjustable toward and from the fixed part to change the width of the groove. Rolls of this kind, however, cannot be adjusted to accommodate bars 45 which are wider at one edge than at the other edge. In accordance with my invention, rolls having only one of their roll parts adjustable may be used on one edge of the bar, but the rolls cooperating with the other edge have both parts 50 adjustable so that the grooves in such rolls may have their side walls spaced at equal distances from a plane midway of the groove walls of the other rolls. In the accompanying drawing, the inner roll is shown as having both roll parts adjustable, since only one inner roll is used, but it

will be understood that the outer rolls may be adjusted in this manner, if desired.

In the embodiment of the invention shown in the drawing, A, Fig. 1, may represent either a top plate or frame member of a bending machine 60 having the roll shafts arranged vertically, or the end plate of a bending machine with horizontal roll shafts. B represents the outside rolls of the bending machine, which may be mounted on shafts journaled in fixed relation to this plate, 65 and C the inside roll which is suitably mounted for adjustment toward and from the outside rolls in any usual or suitable manner, such adjusting means not being shown. In the particular bending machine shown, the outside rolls B are driven 70 and each roll B is secured on a shaft E, and the roll C is an idler roll, being mounted to rotate about a fixed shaft or axle F. The roll C may, however, be driven if desired.

Each outside roll B, in the particular construction shown, includes a sleeve 5 suitably held against turning on the shaft E, for example, by means of a key 6. The sleeve 5 preferably has an outer sleeve 7 secured thereto in any suitable manner, not shown. The outer sleeve may be 80 made of a hardened or tool steel and the sleeve 5 may be made of a softer and more easily machined metal. The outer sleeve 7 preferably has an outwardly extending annular ridge or part 8, the inner face 9 of which forms one of the side 85 walls of the groove which received the bars to be bent, the annular face of the sleeve 7 forming the base of the groove.

The opposite side wall of the groove is formed by a face 10 of an annular or cylindrical part 11 90 which may also be made of tool steel or other suitably hardened metal and which is secured to the outer portion of a radially extending collar 12. This collar is secured to the shaft E by means of the key 6 and is also held against endwise movement on the shaft E. The sleeve or part 11 may be secured to the collar 12 in any suitable manner, for example, by means of a welded connection indicated by 13. Each roll B, therefore, includes an inner part fixed to the shaft E and consisting of the collar 12 and its annular flange 11, and an outer part, including the sleeves 5 and 8, which is adjustable lengthwise 100 of the shaft E and which may telescopically enter into the cylindrical flange 11.

In order to render the outer part of the roll adjustable relatively to the inner fixed part, to vary the width of the groove formed between these two parts, the sleeve 5 is provided on its outer end with a cap 15 which may be integrally 110

formed therewith and which has a central aperture 16 through which an adjusting screw or stud 17 extends. The inner end of this screw or stud engages in a threaded hole in the end of the shaft E. The screw or stud 17 is also provided with an outwardly extending flange 18 which is adapted to bear against the inner face of the cap portion 15 of the sleeve 5, and if desired, a bearing plate or washer 19 may be inserted between this flange and the cap portion 15. The portion of the screw or stud 17 beyond the flange 18 is preferably also threaded, as indicated at 20, to receive a nut 21 engaging the outer face of the cap portion 15. The outer end of the screw or stud may also be provided with a head 22 by means of which the same can be turned. By means of this arrangement, the width of the groove between the walls 9 and 10 can be readily adjusted by first slightly releasing the nut 21 and then turning the screw 17 by means of the head 22 thereof. This causes the screw to enter into, or move out of, the threaded hole in the end of the shaft E, and this movement of the screw causes a corresponding movement of the sleeve 5. When the desired adjustment is reached, the nut 21 is tightened so that the parts will be securely locked in place. It will be noted that in this roll only one of the side walls of the groove, namely, the side wall 9, is adjusted, the other side wall 10 remaining in fixed relation to the shaft E.

Referring now to the roll C, this roll also includes an inner sleeve 25 which, in the construction shown, is journaled to rotate freely about the stud or fixed shaft F, a bearing sleeve 26 being for this purpose inserted between the sleeve 25 and the stud F. The sleeve 25 near the inner end of the roll has a radially extending flange 27 to which a cylindrical part or sleeve 28 may be rigidly secured, for example, by means of welding as indicated at 29. The outer edge of the band or sleeve 28 forms a wall 30 of the groove in this roll and in order to adjust this wall 30 toward and from the center of the groove in this roll, any suitable adjusting means cooperating with the shaft or axle F may be employed. In the particular construction shown for this purpose, the outer end of the sleeve 25 may be provided with a transversely extending web 31 having a central aperture 32, and a screw-threaded bolt or adjusting screw 35 is provided, the inner threaded end of which is adapted to engage with a correspondingly threaded aperture in the end of the stud shaft F. This adjusting screw 35 is preferably also provided with an annular, outwardly extending flange 36 adapted to bear against the inner face of the web 31, a bearing disk or washer 37 being provided for this purpose in the construction shown. The portion of this screw 35 which extends beyond the transverse web 31 of the sleeve 25 is preferably also threaded and adapted to receive a nut 38, which may be suitably locked in place on this end of the adjusting screw 35 in any suitable manner. For example, this nut may be split, as indicated at 39, and a clamping screw 40, having a threaded engagement with a part of the nut 38 at one side of the split and pressing against the other side, may be employed to lock the nut 38 securely on the threads of the bolt 35. Any other means for this purpose may be employed.

Any suitable means may also be provided for locking the adjusting screw 35 in the threaded hole in the fixed shaft or axle F and, in the construction shown for this purpose, the screw 35 may be split, as indicated by the slot 42 therein,

and the split end may be expanded to grip the wall of the threaded aperture in the axle or shaft F. The gripping means may include a bolt 43 which extends lengthwise through a bore or central aperture in the adjusting screw 35, and the inner end of this locking bolt is provided with a tapered head 44 which preferably engages with a correspondingly tapered end of the bore in the adjusting screw 35. Consequently, it will be obvious that if the locking bolt 43 is drawn outwardly with reference to the adjusting screw 35, as by tightening a nut 45 engaging the threaded end of the bolt 43 and bearing against the end of the screw 35, the tapered sides of the head 44 will engage with the correspondingly tapered inner face of the bore in the adjusting screw and will thus spread or separate the lower split ends of this screw, and thus press the same into engagement with the threaded hole in the fixed shaft F. Consequently, the adjusting screw 35 can be easily adjusted lengthwise of the shaft or axle F and such adjustment results in a corresponding adjustment of the part of the bending roll C which includes the sleeve 25 and annular member 28. To facilitate such adjustment the outer end of the screw 35 is preferably formed to enable it to be gripped by a wrench, for example, by providing a hexagonal end 46 on the screw 35. Consequently, when it is desired to change the adjustment of the sleeve 25 and of the wall 30 of the groove, the nut 45 is first loosened and the outer end of the bolt 43 may be tapped slightly to release the wedge end 44 thereof from the bore in the adjusting screw 35. The screw 35 is then released from its clamping action and is free to be turned by means of a wrench engaging the head 46 of the screw. The flange 36 and the nut 38 will transmit to the sleeve 25 any longitudinal adjustment of the screw 35, and when the desired adjustment has been made, the nut 45 is tightened to again clamp the screw 35 in its adjusted position.

The inner roll C also includes another adjustable part forming the opposite side wall of the groove and also the base of the groove in this roll. This part of the roll in the construction shown includes a sleeve 48 having an outwardly extending flange 49 forming the opposite side wall of the groove, the cylindrical portion of the sleeve 48 forming the base of the groove. The sleeve 48 is movable lengthwise of the sleeve 25 of the other part of the roll and a portion of the sleeve 48 may telescopically enter within the cylindrical member 28. Adjustment of the sleeve 48 may be effected in any suitable or desired manner. In the construction shown, the sleeve 48 has an extension 50 suitably secured thereto, for example, by means of bolts 51 and the outer end of this extension is threaded to engage with a threaded portion 52 at the outer end of the sleeve 25. The threaded part of the extension 50 may be split and provided at opposite sides of the split with lugs or projections 53 through which a clamping bolt 54 extends for clamping the threaded part of the extension 50 against the threaded portion 52 to hold the collar 48 in fixed relation to the sleeve 25. When it is desired to change the adjustment of the sleeve 48, the bolt 54 is released so that the extension 50 with the sleeve 48 secured thereto can be freely rotated lengthwise of the threaded portion 52. The rotation of the sleeve 48 and extension 50 provides for the adjustment of these parts lengthwise of the axis of this roll, and when the desired adjustment has been made, the bolt 54 is again tight-

ened. Any other means for adjusting the sleeve 48 lengthwise of the sleeve 25 may be provided, if desired.

In the use of the bending rolls illustrated, if a bar is to be bent on edge as indicated in the drawings, the groove in the outer bending rolls is adjusted to receive the outer end of the bar. The groove in the inner bending roll is then adjusted in such a way that the opposite sides of this groove will be spaced at substantially equal distances from the central plane of the work, which central plane will also coincide with the centers of the grooves in the outer bending rolls. Because of the upsetting of the inner edge portion of the bar or work X, each of the walls of the groove in the inner bending roll will have to be located at a slightly greater distance from this plane than the corresponding walls of the grooves in the outer rolls. Consequently, in adjusting a machine to operate on a bar of a certain size, the outer rolls are adjusted so that the walls 9 and 10 of the grooves in these rolls are spaced apart as may be necessary according to the width of the bar X. The side wall 30 of the groove of the inner roll is then set in a plane slightly below the plane of the side walls 10 of the outer rolls as indicated in Fig. 2. The upper side wall of the groove formed by the flange 49 is then set slightly above the plane of the side walls 9 of the grooves in the outer rolls. Both of the side walls of the groove of the inner roll will, therefore, be spaced approximately equidistant from a plane extending midway between the side walls of all of the grooves of the rolls and midway of the work.

By means of this arrangement, the machine can be readily adjusted to operate on bars of different shapes or sizes without removing the rolls from their shafts or bearings. While the inner roll has been described as having both of the side walls of the groove adjustable, it will be obvious that this arrangement can be reversed by providing an adjustment on the two outer rolls similar to that shown on the inner roll in the construction illustrated, and by making the inner roll of a construction similar to that illustrated in connection with the outer rolls. In such a case, the inner roll would be adjusted with a groove of sufficient width to receive the enlarged or upset edge of the bar and the side walls of the grooves of the outer rolls would be set to form narrower grooves, but equi-distant from the central plane of the bar. Since, however, it is only necessary to provide an adjustment of both side walls of the groove or grooves at either one or the other edge of the work, it is, of course, more expedient to provide such adjustment only on the inner roll and employing adjustment for only one groove wall for the outside rolls.

60 I claim as my invention:

1. A bending machine roll for bending flat bars on edge, including parts forming opposite sides of a groove, a cylindrical part forming the bottom of the groove and against which the edges of the bars bear, said side parts having portions connecting therewith extending to one end of said roll, and means on said end of said roll and cooperating with said portions for adjusting each of said side parts relatively to the other.

70 2. A bending machine for bending flat bars on edge and having rolls arranged inside and outside with reference to the curvature of the work, said outside rolls having adjustable parts arranged to form grooves of different widths to receive the work, said inside roll having parts form-

ing the side walls of a groove, and means for adjusting both of said parts toward and from a plane passing through the centers of the grooves of said outside rolls, all of said rolls having cylindrical portions forming the bottoms of said groove and against which the work bears. 80

3. A bending machine roll having parts adjustable relatively to each other to form the side walls of an annular groove for the work, a cylindrical part forming the bottom of the groove and on which the work bears, a shaft on which said parts are mounted, one of said side wall parts being adjustable lengthwise of said shaft and the other side wall part being adjustable relatively to said first side wall part. 85

4. A bending machine roll having parts adjustable relatively to each other to form the side walls of an annular groove for the work, a cylindrical part forming the bottom of the groove and on which the work bears, a shaft on which said parts are mounted, one of said parts having a sleeve arranged about said shaft, means at one end of said sleeve and cooperating with said shaft for adjusting one of said side wall parts lengthwise of said shaft, and means for adjusting said other side wall part relatively to said first side wall part. 90

5. A bending machine roll having parts adjustable relatively to each other to form between them an annular groove for the work, a shaft 105 on which said parts are mounted, one of said parts having a sleeve arranged about said shaft, means at one end of said sleeve and cooperating with said shaft for adjusting said part lengthwise of said shaft, and means cooperating with said 110 sleeve and said other part for adjusting said other part lengthwise of said shaft relatively to said first part.

6. A bending machine roll having parts adapted to cooperate to form between them an annular groove, one of said parts including a radially extending part having a cylindrical member secured thereto, one end of said cylindrical member forming a side wall of said groove, the other part of said roll including a sleeve adapted to telescope into said cylindrical member and forming the base of said groove, and having a flange forming the other side wall of said groove, and means for adjusting one of said parts relatively to the other to vary the width of said groove. 115

7. A bending machine roll having a pair of annular parts adjustable toward and from each other to form between them an annular groove to receive the work, one of said parts including a sleeve, a shaft extending into said sleeve, an adjusting screw engaging in a threaded hole in said shaft and having a connection with said sleeve for adjusting said sleeve lengthwise of said shaft, and means for adjustably securing the other part of said roll to said sleeve. 120

8. A bending machine roll having a pair of annular parts adjustable toward and from each other to form between them an annular groove to receive the work, one of said parts including a sleeve, a shaft extending into said sleeve, an adjusting screw engaging in a threaded hole in said shaft and having a connection with said sleeve for adjusting said sleeve lengthwise of said shaft, and a screw threaded connection be-

145

between said sleeve and said other part of said roll for adjusting said other part lengthwise of said sleeve to vary the width of said groove.

9. A bending machine having rolls arranged inside and outside with reference to the curvature 150 of the work, said inside roll including two an-

5 nular parts forming between them a groove to receive the work, one of said annular parts having a sleeve of smaller diameter than said other annular part against which the work may bear and which telescopes within the other annular part, and means for adjusting said annular parts in opposite directions from the center of the groove.

10 10. A bending machine roll for bending flat bars on edge, including a pair of annular parts forming between them an annular groove to receive the work, one of said parts having a cylindrical portion of less diameter than said other part and movable into and out of a corresponding recess in the other part during adjustment of said parts relatively to each other, said cylindrical portion bearing against the edges of the bars, and means for adjusting said annular parts in opposite directions from the center of said 20 groove.

11 11. A bending machine for bending flat bars on edge and having rolls arranged inside and outside with reference to the curvature of the work, each of said rolls having a work receiv- 25

ing groove therein provided with side walls and a bottom wall by means of which bending pressure is transmitted to the work, the outside rolls each having at least one side wall adjustable to vary the width of the groove to receive work 80 of different sizes, and the inside roll having both of its side walls adjustable toward and from each other.

12 12. A bending machine for bending flat bars on edge and having rolls arranged inside and 85 outside with reference to the curvature of the work, each of said rolls having a work receiving groove therein provided with a bottom wall adapted to engage an edge of the work to exert bending pressure thereon, said grooves also having side walls which are adapted to engage portions of the sides of the work, and means for adjusting the side walls of the groove of the inside roll to form on said inside roll a groove 90 of greater width than the grooves of said outside rolls and with the side walls of the groove of said inside roll spaced substantially equidistant from the central plane of the work. 95
